ABSTRACT

An apparatus for supporting the hand or foot during convalescence thereof including a frame comprising two substantially parallel rods, a frame supporting member comprising rods extending in angular relation from said frame for contact with a supporting surface to thereby maintain said frame in spaced relation from said supporting surface, a holding rod connected to one end of said frame for extension through the forelimb of the patient, a plurality of substantially parallel extending bars connected to said frame adjacent the end thereof opposite said holding rod and extending from said frame in substantial angular relationship thereto, and a supporting member attached to said frame intermediate the ends thereof, said supporting member having a generally rounded upper surface for fitting into the palm of and supporting a hand or foot.

LIMB SUPPORTING DEVICE

BACKGROUND OF THE INVENTION

The present invention relates to a limb supporting device. More particularly, the present invention relates to a device for supporting limbs, particularly the extremities thereof, during convalescence of such limbs.

During periods when badly burned hands are in the process of healing, there is a tendency for the fingers to be drawn into a deformed position. If the hand heals with the fingers in such deformed position, it becomes difficult to impossible for the patient to ever again fully extend and have full use of the fingers. Therefore, it is desirable to have means to prevent the fingers from being drawn toward the deformed position. However, because of the long period required for the healing of bad burns and like damage to the soft tissues of the hand, it is quite difficult to find means for preventing the contracting or deforming of the fingers which does not cause other damage to the limbs involved. Also, because of the sensitivity of the injured member, it is difficult to find means of preventing the deforming of the fingers which does not inflict considerable pain on the patient or injure the healing processes.

It is an object of the present invention to provide a device for preventing the contraction of the digits of a hand or foot during the healing period of the soft tissues of such hand or foot.

Another object of the present invention is to provide a device for maintaining the digits of badly burned or similarly damaged hands or feet in extended position during the healing of such hands or feet to thereby prevent permanent contraction of such digits during such healing process.

A remaining object of the present invention is to provide an apparatus for supporting the extremities of arm or leg members during skin grafting on the arm or leg or the forearm or foreleg.

SUMMARY OF THE INVENTION

The present invention, which fulfills the above and other objects, is an apparatus including a frame comprising two substantially parallel rods, a frame supporting member comprising rods extending in angular relation from said frame for contact with a supporting surface to thereby maintain said frame in spaced relation from said supporting surface, a holding rod connected to one end of said frame for extension through the forelimb of the patient, a plurality of substantially parallel extending bars connected to said frame adjacent the end thereof opposite said holding rod and extending from said frame in substantial angular relationship thereto, and a supporting member attached to said frame intermediate the ends thereof, said supporting member having a generally rounded upper surface for fitting into the palm of and supporting a hand or foot.

By means of the apparatus of the present invention, a hand or foot may be maintained in fixed position with the digits thereof extended as desired. This is accomplished in such manner that the supported hand or foot is well protected from external forces and with a minimum of pain and discomfort to the patient.

DESCRIPTION OF THE DRAWINGS

FIG. 1 of the drawings is an isometric view of an embodiment of the apparatus of the present invention.

FIG. 2 of the drawings is a side elevational view of the embodiment of the apparatus of the present invention illustrated in FIG. 1.

FIG. 3 of the drawings is a front elevational view of the embodiment of the apparatus of the present invention illustrated in FIG. 1.

DESCRIPTION OF THE PREFERRED EMBODIMENTS OF THE PRESENT INVENTION

To further describe the present invention, reference is made to the accompanying drawings. In the drawings, the same reference characters are used throughout to denote like features of the apparatus of the present invention.

Referring to the drawings, a frame 10 is provided as a basic structure from which all other features of the present apparatus extend. Frame 10 is comprised of two substantially parallel spaced apart rods 11 and 12. Generally, rods 11 and 12 are spaced apart a distance at least approximately equal to the width of the member to be suspended therein which may be either a hand or a foot, generally a hand since the most useful application of the apparatus of the present invention is in the treating of the hands.

At one end, frame rods 11 and 12 extend into converging sections 13 and 14 which, while converging toward one another, diverge with respect to the plane common to both rods 11 and 12. In other words, considering frame 10 as being substantially horizontal, one of either sections 13 or 14 extends downward while the other extends upward while both extend toward one another insofar as a vertical plane is concerned. The extension of rod sections 13 and 14 is such that the terminal ends 15 and 16, respectively, thereof lie upon an imaginary line which is substantially perpendicular to the plane in which frame 10 lies. Again, assuming frame 10 to lie in a substantially horizontal plane, terminal ends 15 and 16 are in substantially vertical alignment with respect to one another.

Terminal ends 15 and 16 are adapted by means of circular segments thereof to receive and hold clamps 17 and 18, respectively. Clamps 17 and 18 are each provided with openings therethrough to receive restraining pin 19 which passes through the openings in clamps 17 and 18 in slideable contact with the walls thereof. To hold pin 19 in rigid position, clamps 17 and 18 are provided with screws 20 which are threaded through the walls of clamps 17 and 18 to open into adjustable contact with pin 19 within the opening of the clamps. Screws 20 generally have a wing or extended plate head for easy manipulation in adjusting screws 20 into or out of contact with pin 19. In some instances, it may be necessary to provide two or more pins 19 in which case terminal ends 15 and 16 are extended beyond clamps 17 and 18 to a second or other pair of such clamps which hold the additional pins 19.

In the embodiment of the apparatus shown in the drawings, frame rods 11 and 12 come together in a continuous manner at the end opposite sections 13 and 14 in such manner as to form a loop 21. If desired, the apparatus of the present invention may be supported in use by means of attachment of a line to loop 21 and some stationary object. In addition, by forming loop 21 as a circular joined extension of rod frames 11 and 12, some energy absorbing flexibility is imparted to frame 10 which permits less discomfort and damage to the patient in the event of an unanticipated force striking frame 10.

Connected to frame 10 are two frame supporting members 22 and 23. Both frame supporting members 22 and 23 comprise two leg segments 24a and 24b respectively which are joined by base segments 25a and 25b, respectively. The ends of leg segments 24a opposite the joinder to base segment 25a are slideably connected to frame rods 11 and 12 by means of clamps 26. The leg segments 24a and 24b of frame supporting members 22 and 23 respectively extend in angular relationship to frame rods 11 and 12, preferably at approximately right angles, to thereby provide a supporting frame for contacting a supporting surface such as a table, platform, bed, etc. to maintain frame 10 in spaced apart relation from said supporting surface. Generally, the two frame supporting members 22 and 23 extend in opposite directions from said frame 10 to thereby provide support for frame 10 regardless of which way it may be turned. In addition to serving as supports for frame 10, frame supporting members 22 and 23 provide frames to which strings, wires, bands, etc., may be attached for aid in maintaining positioning of the patient's hand or foot, as the

case may be, in the desired treating position. By the loosening of clamps 26, frame supporting members 22 and 23 may be moved along the length of frame 10 to the most advantageous supporting position at which position clamps 26 are tightened to thereby retain frame supporting members 22 and 23 in such advantageous supporting position.

Extending at an angle, preferably about 90°, from adjacent the end of frame 10 opposite terminal ends 15 and 16 are a plurality, generally four, of rods 27. Usually, a base bar 28 extending between frame rods 11 and 12 serves as a base from which rods 27 extend. Base bar 28 generally is in slideable but clampable contact with frame rods 11 and 12 through an adjusting clamp 29. By loosening adjusting clamps 29, base bar 28 may be moved along the length of frame 10 for the most advantageous positioning of rods 27 with respect to their intended use which is more fully described below.

Rods 27 are curved intermediate the ends thereof, preferably, through an approximately 90° turn, thereby forming an outer segment 30. In the preferred embodiment in which said curve is approximately 90°, outer segment 30 lies in substantially parallel relationship to frame rods 11 and 12. Outer segments 30 of rods 27 extend generally toward terminal ends 15 and 16 of frame rods 11 and 12, respectively. Also, the distance of outer segments 30 from frame rods 11 and 12 usually is less than the distance of the base segments 25a and 25b, respectively of supporting members 22 or 23, as the case may be, from frame rods 11 and 12, thereby providing for such outer segments 30 to be spaced apart from the supporting surface by means of such supporting members 22 or 23, as the case may be.

In slideable but clampable contact with rods 27 are adjustable anchor means 31, one to each of rods 27. By loosening adjusting screw 32, anchor means 31 may be moved along the length of rod 27 including outer segment 30. Tightening of screw 32, conversely, provides fixed and stationary attachment of anchor means 31 to rods 27. The purpose of anchor means 31 is to provide a tiedown for strings, wires, bands, strips, and the like attached to the ends of the digits of the outer limb of the patient. As a result of the adjustable nature of both base bar 28 and anchor means 31, optimum adjustment of the apparatus of the present invention to fit the size and shape of the hand or foot of the patient is readily obtainable.

Disposed within frame 10 intermediate the ends thereof is a supporting member 33. While supporting member 33 may be connected to frame 10 by any number of means, such means generally have in common the provision of a slideable and adjustable connection of supporting member 33 to frame 10. Supporting member 33 may be suspended between frame rods 11 and 12 of frame 10 by means of a substantially straight bar extending through such supported member and in slideable but clampable contact with such rods 11 and 12. Alternatively, as shown in the drawings, supporting member 33 is supported by a bar 34 which is joined at the ends thereof by extension rods 35 which lie substantially at right angles thereto, extension rods 35 extending forward into slideable but adjustable contact with base bar 28. In this embodiment, extension rods 35 lie substantially parallel to frame rods 11 and 12. The slideable and adjustable contact of extension rods 35 with base bar 28 is through adjustable clamps 36 which are in fixed attachment to base bar 28 but in slideable but clampable contact with extension rods 35. In some instances, it may be necessary to provide for rotational mounting of extension rods 35 to base bar 28 to permit supporting member 33 to be lowered significantly below the plane in which frame 10 lies. Particularly, may this be necessary for the foot. Of course, any number of other means may be provided for lowering the supporting member 33 below the plane of frame 10 but such other means are within the spirit and scope of the present invention.

Supporting member 33 generally is rounded upon its upper surface as shown in the drawings. Usually, this member will be rounded to fit the palm of the particular hand or foot which will be supported thereby. A particularly useful shape for sup-

porting member 33 is substantially conical, the direction of the apex depending on the particular hand or foot to be placed thereupon. The material of construction of the supporting member may vary considerably. Such materials as plastics, rubber, metals, woods, and the like may be used. However, it has been found particularly advantageous to employ an ordinary cylindrical shaped cork such as is often employed as a float in fishing. In using the apparatus of the present invention, the patient's hand or foot is placed within the apparatus with the palm thereof in contact with the upper surface of supporting member 33. Restraining pin 19 is then placed through the forearm or foreleg, as the case may be, and fastened within clamps 17 and 18 to thereby restrain the member within the apparatus of the present invention. Pins through the outer tips of the digits of the hand or foot or other means for attachment of the line to such outer tips, are provided, and a line, preferably a tension producing elastic material, is connected to such pin or other means and then extended into attachment to anchor means 31. Thereby, such digits are retained in extended relation to the hand or foot during the healing process. For comfort or other reasons, the apparatus of the present invention may be adjusted to the individual through the various means hereinabove described for adjusting the various elements of the apparatus of the present invention. The thus suspended hand or foot is supported by the present apparatus by placing a base bar 25 into contact with a supporting surface such as a table, platform, or the like, or by means of attachment of a line to loop 21 which line then is attached to some stationary object to thereby support the present apparatus.

What is claimed is:

1. An apparatus including a frame comprising two substantially parallel rods spaced by a base bar, a frame supporting member comprising rods extending in angular relation connected to said frame for contact with a supporting surface to thereby maintain said frame in spaced relation from said supporting surface, a holding rod connected to one end of said frame for extension through the forelimb of the patient, a plurality of substantially parallel extending bars connected to said base bar located adjacent the end thereof opposite said holding rod and extending from said base bar in substantial angular relationship thereto, and a supporting member attached to said frame intermediate the ends thereof, said supporting member having a generally rounded upper surface for fitting into the palm of and supporting a hand or foot.
2. The apparatus of claim 1 wherein said holding rod is in slideable and clampable connection with said frame and positioned thereby such as to be substantially perpendicular to the plane of said frame.
3. The apparatus of claim 1 wherein said supporting member is conical in shape.
4. The apparatus of claim 1 wherein two of said frame supporting members are provided, one extending from either side of said frame in substantial perpendicular relationship thereto.
5. The apparatus of claim 1 wherein said plurality of substantially parallel extending bars consists of four of said bars.
6. The apparatus of claim 1 wherein said extending bars are bent intermediate the ends thereof such that an outer segment thereof extends directionally toward said end of said frame having connected thereto said holding rod.
7. The apparatus of claim 1 wherein each of said extending bars has in slideable and clampable connection therewith an anchor means.
8. The apparatus of claim 1 wherein said supporting member is in slideable connection with said frame.
9. The apparatus of claim 1 wherein said two substantially parallel rods of said frame extend into a looped joinder thereof at the ends thereof opposite said holding rod to thereby provide an expandable-contractable loop adjacent said joinder.
10. The apparatus of claim 1 wherein said extending bars are in slideable and clampable connection with said frame such as to permit adjustable movement of said extending bars about the length of said frame.
